UNITED STATES PATENT OFFICE

ERNEST HAMWI, OF ST. LOUIS, MISSOURI

DESIGN FOR AN EDIBLE PASTRY CUP

Application filed September 13, 1929. Serial No. 32,747. Term of patent 14 years.

To all whom it may concern:

Be it known that I, ERNEST HAMWI, a citizen of the United States, residing at the city of St. Louis and State of Missouri, have invented a new, original, and ornamental Design for Edible Pastry Cup, substantially as shown in the accompanying drawing, in which—

Fig. 1 is a plan view of the edible pastry cup showing my new design.

Fig. 2 is a side elevation.

Fig. 3 is a vertical diagrammatical sectional view.

I claim:

The ornamental design for an edible pastry cup, substantially as shown.

ERNEST HAMWI.
